STANLEY A. COMISKEY, OF SEATTLE, WASHINGTON, ASSIGNOR TO R. HOE & CO., INC., OF NEW YORK, N. Y., A CORPORATION OF NEW YORK.

SHEET DETECTOR.

Application filed November 20, 1924. Serial No. 750,983.

This invention relates to certain improvements in detector mechanism for stopping a web handling machine in case of a break in a web, such as a printing press.

In certain web handling machines, such as printing presses, it is very desirable to stop the machine in case of a break in the web to prevent web wastage.

Detector mechanisms have been employed to effect this, a movement of the detector caused by a break in the web operating a switch or like device which stops the machine. With such mechanisms, however, as has heretofore been used, it has been necessary to reset the switch mechanism by hand after it is operated. In large web handling machines, such as multi-couple printing machines, a large number of these detectors are used at different points in the machine. Heretofore, after a break in the web and the web has been again threaded through the machine, it has been necessary for the pressmen to hunt around to find which detector is out, that is, which detector needs to be reset. Where a considerable number of these mechanisms are used, therefore, a considerable amount of time is lost in locating the detector that needs to be reset before the running of the machine can again be resumed.

It is a special object of the present invention to provide a detector mechanism which will indicate a break in a web and will act to stop the press, and which will automatically reset the switch mechanism in operative position, after it has functioned to stop the machine, so that the pressmen will not have to waste time in looking for the detector which has caused the stoppage of the machine.

A further object of the invention is to provide a mechanism in which the detector member may be locked in an inoperative position for convenience in threading a web through the machine, or for any other desired purpose.

It is a further object of the invention to provide a detector mechanism which shall be small in construction and accurate in operation, and which may be readily positioned in the machine with which it is to be used.

With these and other objects not specifically referred to, the invention consists in certain novel parts, arrangements and combinations which will be described in connection with

the accompanying drawings and the novel features pointed out in the claims hereunto annexed.

In these drawings,—

Figure 1 is a side view of the detector mechanism showing the parts in the position they occupy when the detector feeler or member is in contact with the web;

Figure 2 is a similar view showing the parts in the position they occupy when a break in the web has caused the detector mechanism to operate;

Figure 3 is a view showing the position of the parts after such break, and in which the switch mechanism has been automatically returned to operative position;

Figure 4 is a view showing the position of the parts when the detector feeler is lifted out of the way and locked to permit free threading of the web;

Figure 5 is a plan view on a somewhat enlarged scale, the view being taken on the line 5—5 of Figure 3, looking in the direction of the arrow 3 in that figure;

Figure 6 is a detail sectional view of the switch mechanism, the switch being shown in on position;

Figure 7 is a view similar to Figure 6 showing the switch in off position, and

Figure 8 is a diagrammatic view of a printing machine showing one way in which the detector may be associated therewith; this figure also showing the driving motor for the machine and the motor and switch circuits.

While the construction selected to illustrate the invention is a printing machine in which the sheet is in the form of a web, it will be understood that the detector mechanism, as to certain of its features, is designed for and is capable of use with other types of machines and with machines in which a sheet as distinguished from a web is being fed.

In the construction illustrated, however, a printing machine is shown, including side frames 1, 2, in which is supported a rotary printing couple, the cylinders of which are marked 3, 4 and its inking mechanism 5; a second printing couple, the cylinders of which are marked 7, 8 and the inking mechanisms 9; a third printing couple, the cylinders of which are marked 10, 11 and the inking mechanism 12, and a fourth couple, the cylinders of which are marked 13, 14 and the linking mechanism 15. These printing

machines are fed from web rolls R and R' and the products delivered to a folder, designated generally by the numeral F.

This press is driven from a motor M, the 5 driving connections from the motor being of any suitable character, as a belt 16 and a pulley 17 on a line shaft 18, connections from the line shaft to the printing couples being by means of miters 19, 20, 21, 22.

10 Two of these presses, as the presses 3, 4, 7, 8, are shown as each provided with a detector mechanism, indicated generally by D, these detector mechanisms being in circuit with the motor through circuits a, b and 15 switch c, so that by the operation of these detector mechanisms the motor and, consequently, the press are stopped.

It will be understood that as many of 20 these detector mechanisms as may be desired will be supplied at various points in the machine, two having been shown in Fig. 8 as illustrative of the invention, such mechanism all being in circuit with the driving motors of the press.

25 The specific construction of the detector mechanism may vary, but a preferred construction is that shown in the drawings, and such a construction will now be described.

30 The detector mechanism shown includes a two-part casing 23, 24, the parts of the casing being secured together in any suitable manner, as by bolts 25 passing through ears 26, 27 formed on the casing walls. The base 35 of the casing is provided with extensions 28, 29 to which are secured by bolts 30 end bracket 31, 32 (best shown in Fig. 5) by which the casing is supported in the frame of the machine, as shown in Fig. 8. The 40 outer part 23 of the casing is provided with a pair of spaced legs or extensions 33, 34, having at their outer ends bearings 36 for a stud 37, this stud being secured in place by a cotter pin 38. Pivotedly mounted on this 45 stud is a hub 39 having a flat plate arm 40 to which is secured, by screws 41, a detector member shown in the form of a feeler finger 42 having a curved end 43 which normally engages with the web. The hub 39, opposite 50 the plate arm 40, is provided with a striker 44 having a rounded end 45, this striker working in the space between the legs 33, 34, before referred to.

55 Located in the casing is a switch mechanism which is operated by the striker when the detector is moved due to a break in the web, the striker acting to throw the switch and cut out the driving motor. While this switch mechanism may be of any suitable 60 character, in the best constructions it will be a spring operated mechanism, so that when the striker is moved out of the way the switch will automatically return to operative position. In the specific structure illustrated, this switch mechanism includes a

block 46 in which seats, at one end, an actuator or push-rod 47, this push-rod being surrounded by a spiral spring 48. This push-rod at its outer end, or its left hand end looking at Fig. 6, carries a button 49 70 which operates through a suitable aperture in the casing wall, and this button inside the casing wall is provided with a projection 50 which engages a stop piece 50' to limit its outward movement. 75

Mounted on the push-rod, on the inside of the casing, is a collar 51 which carries a contact flange 51' which is dimensioned to make contact with two contact members 52, 53, these members, as shown, being in the 80 form of uprights having inturned contacting ends 54. These standards, at their lower ends, are formed with legs 55 and are secured on the block 46 by binding posts 56, which also carry the usual binding nuts 57, 58 by 85 which the wires a, b are secured in the switch. If desired, stops 59 may be provided for limiting the inward movement of the plunger so that button 49 will not be forced through the wall of the casing. 90

With the construction so far described, it will be seen that when the detector drops to the position shown in Fig. 2 the point 95 45 of the striker 44 engages the push-button, forcing the latter into the casing and then forcing the contact flange 51' away from the contact faces 54 of the contacts 52, 53, thus breaking the circuit and stopping the motor. In accordance with the invention, means are provided whereby, after this has 100 occurred, the detector is operated so that the striker is freed from the push-button and the switch is allowed to resume its normal or operative position. While this may be accomplished in various ways, in the particular construction illustrated, devices are 105 employed which are actuated by the downward movement of the detector member to produce sufficient power to effect enough of a return movement of the detector finger 110 to cause the striker to free itself from the push-button. In the particular construction illustrated, there is provided for this purpose a small air cylinder 60. The downward movement of the detector causes air 115 to be sufficiently compressed in this cylinder to effect the desired return movement of the mechanism. This cylinder may be mounted and associated with the detector mechanism in any desired manner. As shown, the base 120 of the casing 24 is formed with a boss 61 on which is secured an arm 62, one end of this arm 63 forming a support for the air cylinder 60.

The piston rod 64 of the air cylinder has 125 a split head 65 which is connected by means of a pin 66 to an arm 67 pivotally secured by a bolt 68 to the other end 69 of the arm 62, before referred to. This arm 67 has a recessed or slotted end 70 to receive the end 130

of a second arm 71 which is pivotally connected by a screw bolt 72 to a plate 73 secured to the upper surface of the detector finger 42, before referred to. The upper end 5 of the arm 71 is slightly enlarged, as indicated at 74, so that it will not pull through the slot 70 in the outer end of the arm 67.

In the best constructions, to assist the movement of the air cylinder, the outer end 10 of the arm 67 may be provided with a weight 75 adjustably supported on the arm by a set screw 76, a stop 77 being provided for preventing the weight from being accidentally displaced from the end of the arm.

15 With the construction described, it will be seen that the dropping movement of the detector finger raises the arm 67 on the fulcrum 68, raising the plunger of the air cylinder and compressing air in the cylinder. As 20 soon as the parts have reached the position shown in Fig. 2, the air pressure in the cylinder and the weight cause the parts to assume the position shown in Fig. 3, that is, a lifting movement is given to the detector 25 member, this movement being sufficient to cause the end 45 of the striker 44 to free itself from the push-button 49. The spring 48 in the switch mechanism then returns the plunger to its normal operative position 30 shown in Fig. 6. This results in the parts setting themselves so that after the web is again threaded through the press the machine can be started by throwing in the switch of the motor M without it being necessary to manually throw the switches of the 35 detector mechanisms.

It may be desirable under some circumstances to lift the detector up out of the sheet path and hold it in such elevated position 40 so that a web may be conveniently threaded through the machine. While this may be accomplished in various ways, as shown, the casing of the switch mechanism is provided with a stem 78 on which is provided a latch 45 arm 79 with a hook end 80 which may be hooked under the detector feeler 42 and the parts latched in the position shown in Fig. 4.

50 While the invention has been shown and described in its preferred form, it will be understood that various changes may be made in the specific construction and arrangement of the parts without departing from the invention as defined in the appended claims.

55 What I claim is:

1. In a web handling mechanism, the combination of a detector member located to contact with a web and movable from the web path on breakage of a web, means controlled 60 by the detector member to stop the machine, and means actuated through the movement of the detector member for automatically returning the controlling mechanism to operative position.

65 2. In a web handling mechanism, the com-

bination of a detector member located to contact with a web and movable if a web is broken, an electric switch operated by the detector member to cause the stoppage of the machine, and means actuated through the 70 movement of the detector member for automatically returning the switch to operative position.

3. In a web handling mechanism, the combination of a detector member, an electric 75 switch thrown by the member to cause the stoppage of the machine, and a fluid pressure device associated with the member and acting to move the member to cause the return of the switch to normal operative position. 80

4. In a web handling mechanism, the combination of a detector member located to contact with a web and movable from the web path on breakage of a web, means controlled by the detector member to stop the machine, 85 means for automatically returning the controlling mechanism to operative position, and means for positioning the detector member in inoperative position.

5. In a web handling mechanism, the combination of a detector member located to contact with a web and movable if a web is broken, an electric switch operated by the detector member to cause stoppage of the machine, means for automatically returning 90 the switch to operative position, and means for positioning the detector member in inoperative position.

6. In a sheet detector mechanism, the combination of a detector member, a switch 100 actuated by a movement of the member, and means for moving the member to return the switch to operative position, said means acting through power produced therein by the movement of the detector member.

7. In a sheet detector mechanism, the combination of a detector member, a switch 105 operated thereby, and a fluid pressure device associated with the member for returning the switch to operative position, the pressure 110 in the device being produced by the movement of the detector member.

8. In a sheet detector mechanism, the combination of a detector member, a switch 115 operated thereby, a fluid pressure device for returning the switch to operative position, the pressure in the device being produced by the movement of the detector member, and a weight cooperating with the pressure device.

9. In a sheet detector mechanism, the combination of a movable detector member, an electric switch connected therewith, a finger carried by the member and acting to throw the switch, and an air cylinder for 125 moving the finger out of contact with the switch so that the latter may return to operative position.

10. In a sheet detector mechanism, the combination of a movable detector member, 130

an electric switch connected therewith, a finger carried by the member and acting to throw the switch, an air cylinder for moving the finger out of contact with the switch 5 so that the latter may return to operative position, and a weight for association with the cylinder.

11. In a detector mechanism, the combination of a detector member, a casing by 10 which the detector member is carried, a switch mechanism in the casing, a part carried by the detector member and acting to throw off the switch, and fluid pressure devices associated with the casing for moving 15 the part out of contact with the switch so that the latter may return to operative position.

12. In a detector mechanism, the combination of a detector member, a casing to 20 which the detector member is secured, a switch mechanism in the casing including a plunger, a part carried by the detector member and engaging the plunger to throw the switch, and an air cylinder associated 25 with the casing and acting to move the part out of engagement with the switch, said air cylinder having air therein put under pressure by the movement of the detector finger.

13. In a detector mechanism, the combination of a detector member, a casing to 30 which the detector member is secured, a switch mechanism in the casing, a part carried by the detector member and in contact with the switch to throw the same, an air cylinder associated with the casing, an arm pivotally connected with the casing, to which the air cylinder is connected, and a second arm connected with the first arm and with 35 the detector member.

14. In a detector mechanism, the combination of a detector member, a casing by 40 which the detector member is carried and having means for securing it in operative position in a press, a switch mechanism in the casing, means operated by the detector member to throw off the switch, and a fluid pressure cylinder associated with the casing for causing the return of the switch to on position. 45

15. In a detector mechanism, the combination of a switch mechanism, a pivoted detector finger, a striker operated thereby for throwing off the switch, mechanism actuated through the movement of the detector finger for moving the striker out of contact with 55 the switch, and a spring for moving the switch to on position. 50

16. In a stop mechanism for printing presses, the combination of a detector member movable on breakage of a web, means 60 controlled by the detector member to stop the press, and means put under compression by the movement of the detector member and acting to cause a return movement of the member for automatically returning the 65 controlling mechanism to operative position.

17. In a stop mechanism for printing press, the combination of a detector member movable on breakage of a web, means controlled by the detector member to stop the 70 press, and mechanism put under compression by the movement of the detector member for effecting a movement of the detector member for causing the return of the controlling mechanism to operative position. 75

In testimony whereof, I have hereunto set my hand.

STANLEY A. COMISKEY.
